KEY CASE

Daniel J. Nash, Jersey City, N.J., assignor to Nash Inc., Jersey City, N.J., a corporation of New Jersey

Application May 16, 1957, Serial No. 659,584

1 Claim. (Cl. 150—40)

2

legs having a recess formed in the surface thereof confronting said other leg to permit registry therewith of a key engaging member shank portion when said wings are in closed position.

5 Referring now to the drawings and more particularly to Figures 1 through 4 thereof which illustrate a preferred embodiment of the present invention, the key case comprises a frame including a pair of complementary shaped wing members 10 of U-shaped configuration having cross arms 12 and laterally spaced legs 14 and 15, the ends of legs 14 and 15 of each wing 10 being pivotally connected to the corresponding ends of the legs 14 and 15 of the other wing 10 to form a hinged connection. Spring means, not shown, may be provided normally to urge wings 10 to an open position thereby to expose the interior of the case.

10 In order to lock wings 10 in the closed position, as illustrated in Figure 2 of the drawing, a latch member 16 is hinged to cross arm 12 of one of wings 10 and is provided with a depending wall 18 and is spring urged counterclockwise to a lock position as viewed in Figure 1 of the drawing. A detent 20 is formed in cross arm 12 of opposite wing 10 and is engaged by latch member 16 when wings 10 are in closed position. By depressing an end of latch member 16 so as to rotate it clockwise detent 20 is released and wings 10 may be sprung or otherwise urged to open position.

15 Cross arms 12 and legs 14 and 15 of wings 10 are of roughly semi-circular tubular cross section having an inwardly directed opening 22 formed along the full lengths thereof. A cover panel 24 of substantially rectangular configuration is folded over along a transverse axis and has its peripheral border registering with openings 22 formed in wings 10 and is tightly clinched in position between the confronting edges of the wing forming member to define the walls of the key case.

20 Still another object of the present invention is to provide an improved key case which permits the use of a selected key while the case is in closed condition.

A further object of the present invention is to provide an improved key case characterized by its attractive appearance, ruggedness and ease of operation.

The above and other objects of the present invention will become apparent from a reading of the following description, taken in conjunction with the accompanying drawings, wherein

25 Figure 1 is a front perspective view of a preferred embodiment of the present invention, illustrated in open position;

Figure 2 is an end elevational view thereof illustrated in closed position;

Figure 3 is a sectional view taken along line 3—3 in Figure 2;

Figure 4 is a sectional view taken along line 4—4 in Figure 2;

Figure 5 is a perspective view of another embodiment of the present invention illustrated in open position;

Figure 6 is an end elevational view thereof illustrated in closed position; and

Figure 7 is a sectional view taken along line 7—7 in Figure 6.

30 In a sense, the present invention contemplates the provision of an improved key case comprising a frame including a pair of U-shaped wing members having cross arms and projecting legs, the ends of corresponding legs of said wing members being hinge-connected, and being movable between an open position, and a closed position wherein said wing members are in abutment, a cover member engaging the cross arms and legs of said wing members and defining the walls of said key case, a base member located within said case in proximity to a pair of adjacent leg members, a plurality of key engaging members terminating in shank portions which are swingably connected to said base member, one of said pair of

thereof. The shank 52 terminates in a ball 56, shank 52 engaging a corresponding slot 44 and ball 56 registering with the interior of the tubular member 38. Thus, the key engaging elements 50 are freely rotatable about the axis of the respective shanks 52 and are swingable about the axis of the tubular member 38. One or more of the key engaging elements 50 may be disengaged from the tubular member 38 or inserted therein by shifting the locking member 48 to unlock position wherein the openings therein register with the openings 46 formed in the tubular member 38 and sliding the ball 56 thereof into the tubular member 38 through the aligned openings. A key K may be applied to each of the key engaging elements 50 by spreading the legs of the loop 54 against the biasing thereof, inserting a leg of the loop through the hole in the key K and permitting the loop to close.

In order to permit the location of the loop 54 and the carried key K exterior of the key case while the case is in closed position, a plurality of recesses 58 are formed in the confronting faces of the wing legs 15 in alignment with the respective slots 44 formed in the tubular member 38. It should be noted that the length of the shanks 52 is greater than the distance between the tubular member 38 and the outer edge of the wing legs 15 so that shanks 52 may register with the openings defined by the confronting recesses 38 without impeding the complete closing of the key case.

The embodiment of the present invention illustrated in Figures 5 through 7 of the drawings is identical with the embodiment first described, differing therefrom only in that in place of a plurality of recesses 58 being formed in the confronting faces of the wing legs 15 an elongated recess 65 extending for substantially the width of the tubular member 38 is formed in the confronting faces of each of the legs 15. Thus, upon the closing of the frame an elongated slot 66 is formed in the closed frame through which a selected key may project. In all other respects the key case illustrated in Figures 5 through 7 of the

4
drawing is identical with that illustrated in Figures 1 through 4 of the drawing, the same numbers designating identical parts.

While there has been described and illustrated preferred embodiments of the present invention, it is apparent that numerous alterations and omissions may be made without departing from the spirit thereof.

I claim:

10 An improved key case comprising a frame including a pair of U-shaped wing members having cross arms and projecting legs, the ends of corresponding legs of said wing members being hinge-connected and being movable between an open position and a closed position wherein said wing members are in abutment, a cover member engaging the cross arms and legs of said wing members and defining the walls of said key case, a base member located within said case in proximity to a pair of adjacent leg members, a plurality of key engaging members terminating in shank portions which are swingably connected to said base member, said key engaging members being longitudinally spaced along said base member, and a plurality of recesses formed in the confronting faces of said pairs of legs to define openings in alignment with said key engaging members.
